UNITED STATES PATENT OFFICE

149,328

DESIGN FOR A CIGARETTE DISPENSER

William Abrams, Chicago, Ill.

Application November 1, 1946, Serial No. 134,424

Term of patent 3½ years

(Cl. D85—2)

To all whom it may concern:

Be it known that I, William Abrams, a citizen of the United States, residing at Chicago, county of Cook, and State of Illinois, have invented a new, original, and ornamental Design for a Cigarette Dispenser, of which the following is a specification, reference being had to the accompanying drawing, forming a part thereof, in which—

Fig. 1 is a top plan view of a cigarette dispenser showing my new design;

Fig. 2 is a side elevational view thereof;

Fig. 3 is an end elevational view thereof.

I claim:

The ornamental design for a cigarette dispenser, as shown.

WILLIAM ABRAMS.
